UNITED STATES PATENT OFFICE.

JAMES H. BAILEY, OF LEADING CREEK, WEST VIRGINIA.

CORN-HOUSE.

SPECIFICATION forming part of Letters Patent No. 331,755, dated December 8, 1885.

Application filed September 23, 1885. Serial No. 177,939. (No model.)

To all whom it may concern:

Be it known that I, JAMES H. BAILEY, a citizen of the United States, residing at Leading Creek, in the county of Lewis and State of West Virginia, have invented a new and useful Improvement in Corn-Houses, of which the following is a specification, reference being had to the accompanying drawings.

This invention relates to improvements in corn-houses, &c.; and the novelty consists in the peculiar construction, arrangement, and adaptation of the various parts for service, substantially as hereinafter fully set forth, and specifically pointed out in the claims.

The invention has for its object to provide a corn-house which shall prevent the entrance of mice, &c., to destroy the corn, which shall be capable of drying green corn by affording free circulation of air therein, or to be used as a smoke-house for drying the corn or meats that may be placed therein, and to provide means for elevating the stairs which lead from the ground thereto.

In the accompanying drawings, Figure 1 is a perspective view of a corn-house constructed in accordance with my invention, parts thereof being broken away and shown in section. Fig. 2 is a longitudinal vertical central sectional view. Fig. 3 is a transverse or cross section on the line $\alpha\alpha$ of Fig. 2.

Like letters of reference denote corresponding parts in all the figures of the annexed drawings, referring to which—

A designates the body of my improved corn-house, of the ordinary shape or construction—*i. e.*, having vertical walls provided with a door, a , and a series of windows, a' , for the introduction of corn or other material to be stored therein, a gable-roof, a^2 , and said body is supported in an elevated position above the ground upon uprights or posts B.

The floor C of the house proper is composed of a series of parallel strips or slats, c , arranged a short distance apart to provide intermediate spaces, c' , for the free entrance and exit of the air, to permit a free circulation thereof through the house, to dry the green corn or other substances placed therein for drying purposes. If desired, a fire may be built beneath the house, and the smoke thereof be permitted to enter to house through the slatted bottom thereof, this provision also affording conven-

ient means for drying or preserving meats, &c. The slatted floor is supported by cross-beams D, secured upon longitudinal beams D', secured to the posts or uprights, and the longitudinal beams are braced by struts d , secured thereto and the uprights in any suitable manner. If desired, lateral braces may be employed, and protecting strips or boards d' may be secured to the uprights.

E designates parallel horizontal rods or strips extending transversely across from one brace or strut to the other, and are employed to support nests or provide roosts for the fowls. At one end of the house a stairway, F, is provided, the upper end thereof being pivotally connected to a strip, f , by any preferable means, and adapted to be closed or drawn upwardly to close the openings in the floor. The stairs are preferably hinged by means of eyes f' , through which passes a rod, f^2 , and to the lower end of the stairs is connected a cord, rope, or chain, g , which passes upwardly into the house proper and over a pulley, G, mounted on a shaft, g' , journaled at its ends in the house, and a frame, h , thence to and over another pulley, h' , and provided with a weight, i , which normally keeps the steps closed upwardly against a strip, j , the under surface of said stairs being provided with a back board, k , to present a smooth exterior face thereto when folded. A metallic plate, b , is secured near or at the upper end of the upright posts B, to prevent the rats, &c., from climbing up the said uprights.

Having thus fully described my invention, what I claim as new, and desire to secure by Letters Patent, is—

1. An elevated corn-house having a stairway pivoted at its upper end, a counterweighted cord connected thereto, and pulleys G h' , substantially as described.

2. A corn-house having a slatted floor, and supported upon uprights, a pair of stairs hinged at its upper end to the floor of said house, and a counterweighted cord connected to said stairs and extending over supporting pulleys, substantially as described.

3. A corn-house supported upon uprights and having an open slatted floor, braces or struts d , transverse rods E, bearing in the braces, a pair of stairs hinged to the floor, a cord connected to said stairs and having a

counter-weight, and supporting-pulleys G h', over which the cord passes, as set forth.

4. A corn-house having a slatted floor, and supported upon uprights above the ground, so 5 that a fire may be built or heating devices arranged under the house, to cause the smoke and heat to pass into the latter through the flooring, as set forth.

In testimony that I claim the foregoing as my own I have hereto affixed my signature in 10 presence of two witnesses.

JAMES H. BAILEY.
